CLAIM

I claim the ornamental design for a chair, as shown and described herein.

DESCRIPTION

Chair

- 1.1 : Perspective
- 1.2 : Right
- 1.3 : Front
- 1.4 : Left
- 1.5 : Top
- 1.6 : Back
- 1.7 : Bottom

Fig. 1.1 shows a perspective view of the chair; Fig. 1.2 shows a right side view of the chair; Fig. 1.3 shows a front view of the chair; Fig. 1.4 shows a left side view of the chair; Fig. 1.5 shows a top view of the chair; Fig. 1.6 shows a back view of the chair; Fig. 1.7 shows a bottom view of the chair. Broken lines are for illustrative purposes only and forms no part of the claimed design.
